UNITED STATES PATENT OFFICE.

WILLIAM KRATZ, OF PHILADELPHIA, PENNSYLVANIA.

DESIGN FOR A HEEL-PLATE.

SPECIFICATION forming part of Design No. 30,162, dated February 7, 1899.

Application filed January 16, 1899. Serial No. 702,376. Term of patent 14 years.

To all whom it may concern:

Be it known that I, WILLIAM KRATZ, a citizen of the United States, residing in the city and county of Philadelphia, State of Pennsylvania, have invented and produced a new and original Design for a Heel-Plate, of which the following is a specification, reference being had to the accompanying drawings, forming part thereof.

- 10 The leading feature of my design for a heel-plate is a body portion having one surface curved and the other face thereof provided with longitudinal ridges and grooves, said ridges having recesses.
- 15 Figure 1 represents a plan view of a heel-plate embodying my design. Fig. 2 represents a section on line $\alpha\alpha$, Fig. 1.

In the drawings, A designates a heel-plate, the same having on one side a curved surface B and on the other face the ridges C and the 20 grooves D therebetween, the ridges C being provided with recesses E.

Having thus described my invention, what I claim as new, and desire to secure by Letters Patent, is—

25 The design for a heel-plate substantially as shown and described.

WILLIAM KRATZ.
